UNITED STATES PATENT OFFICE.

SAM F. KLOHS, OF CHICAGO, ILLINOIS.

CAR-COUPING.

987,997.

Specification of Letters Patent. Patented Mar. 28, 1911.

Application filed July 20, 1908. Serial No. 444,370.

To all whom it may concern:

Be it known that I, SAM F. KLOHS, a citizen of the United States of America, and resident of Chicago, Illinois, have invented 5 a certain new and useful Improvement in Car-Couplers, of which the following is a specification.

My invention relates to improvements in car couplers, and has for its object the production of a device in which the knuckle may be held securely in position.

A further object is the production of a device in which the knuckle may be automatically thrown open when it is desired to 15 couple or uncouple cars.

A further object is the production of a device in which the liability of the introduction of sand within the coupler is reduced to a minimum.

20 A further object is the production of a device in which the locking means will not creep while the train is in motion, of simple and strong construction, and one that is least liable to break or get out of order.

25 These and such other objects as may hereinafter appear, are attained by my device, embodiments of which are illustrated in the accompanying drawings, in which—

Figure 1 represents a top plan view of my 30 device with the lifting pin in section. Fig. 2 represents a sectional view on the line A—A of Fig. 1, with the lifting pin down and lock closed. Fig. 3 represents a sectional view on the line A—A of Fig. 1, with the lifting pin partly up and the lock open. Fig. 4 represents a front elevation of Fig. 1 with the pin up and knuckle removed. Fig. 5 represents a sectional view through 35 the center of the coupler, with the lifting pin up. Fig. 6 represents a horizontal sectional view on line B—B of Fig. 4, with the lock and knuckle in place and knuckle closed. Fig. 7 represents a horizontal sectional view 40 on the line B—B of Fig. 4, with the lock and knuckle in place and knuckle open. Fig. 8 represents a plan view of the knuckle, the dotted lines representing cut-away portions to permit the swing of the knuckle.

50 Like letters of reference indicate like parts in the several figures of the drawing.

Referring now to the drawings—9 represents the coupler head; 10 the shank; 11 the knuckle held pivotally in place by means of the pin 12. The tail 13 of the knuckle is 55 dished at 14 opposite the bearing face 15.

A locking member 16, provided with a journal 17, is adapted to be seated on the tail-piece 13 resting against bearings 18 in the coupler head. These bearings are clearly indicated in dotted lines in Figs. 3 and 6. This 60 locking member comprises a knuckle opener wing 19 and a locking wing 20, and projecting horizontally from the inner face of the locking wing is a lifting pin 21; 22 represents the bearing face and 23 the locking 65 face of the locking wing 20, the bearing face being adapted to move upon the inner circular wall 24 of the coupler head and the locking face being adapted to bear against the vertical bearing face 15 of the tail-piece. 70

The lifting pin 25 is of an angular cross-section, to prevent turning in the opening 26 within which it fits with but little play. This pin is provided with an upwardly extending recess 27 having a lower shoulder 28 and an upper shoulder 29, the upper shoulder being formed with a depressed portion or pocket 30. At the bottom of the pin a portion is cut away (shown at 31) forming a shoulder 32. The upper opening 26 80 and the lower opening 33 in the coupler head, through which this pin passes, are slightly out of vertical alinement, so when the pin 25 is in place it inclines slightly to one side. The depth of the cut-away portion 85 at 31 is such, however, that when the pin is raised until the shoulder 32 rests on the ledge 34 on the inner face of coupler head adjacent the opening 33 the pin is in vertical position, as shown in Fig. 3. The lifting lug 21 on the locking wing is adapted to fit within the recess 27 in the pin, hence the upward and downward movement of the lifting pin carries with it the lifting lug, 90 causing the locking member 16 to revolve on its bearings 18—24, while resting on the top of the tail-piece. The flange 35 at the top of the pin completely closes the opening 26, thus preventing the admission of sand and 95 dirt. The face of the coupler head and exposed parts of knuckle are, of course, the Master Car-Builders' contour lines. 100

Referring now to the operation of my device: Assume the train to be backing, and it is desired to uncouple cars. The lifting pin 105 is raised until the shoulder rests on the ledge. This raises the locking wing out of locking engagement with the knuckle, the knuckle opener wing entering the depression in the top of the tail of the knuckle, as clearly 110

2
shown in Fig. 3. The coupler is now unlocked, and when the car is cut loose by the slackening of the speed of the train, the knuckle is pulled wide open, as shown in 5 Fig. 7. The lifting pin, however, while resting on the ledge, was in the path of the knuckle, and was, consequently, knocked off the ledge and fell until the lower face of the locking wing struck the upper face of the 10 knuckle. When the cars are coupled together, as shown in Fig. 2, one face of the locking wing bears against the bearing face of the knuckle, the line of contact inclining upwardly toward the pin. The opposite 15 side of the locking wing bears against the inner face of the coupler head. The pressure of the tail of the knuckle being nearly at right angles to the sweep of the lock makes it impossible for the lock to move 20 upwardly. Furthermore, any tendency in that direction is overcome by the lug on the lock wedging itself against the pin.

By the use of my device, I get an extensive bearing surface on the knuckle and 25 lock, and for the reasons above given, all danger of creeping is avoided, as this is only liable to occur when cars are moving forward.

The tail of the knuckle is long enough 30 to afford a bearing at all times for the journal of the lock and thus keep it from dropping away from its bearings against the top casing of the coupler head. This bearing against the tail of the knuckle serves as a 35 fulcrum for the knuckle opener wing and also a fulcrum for lifting the lock by means of the lifting pin.

It will be seen that I have produced a simple and efficient device, and so arranged the 40 parts that no undue strain is ever brought upon those parts most liable to fracture, and have at the same time produced a strong and direct-acting coupler.

I claim:

- 45 1. In a car coupler, a head, a knuckle, and an integral locking device and knuckle-opener, said locking device and knuckle-opener resting at all times on the tail of the knuckle.
- 50 2. In a car coupler, a head, a knuckle, and an integral locking device and knuckle-opener, said locking device and knuckle-opener resting at all times on the tail of the knuckle and so adjusted that pressure

through the knuckle forces said lock against 55 the inner face of the coupler.

3. In a car coupler, a head, a knuckle, and an integral locking device and knuckle-opener, said locking device and knuckle-opener resting at all times on the tail of 60 knuckle and so adjusted that pressure through the knuckle forces said lock against the inner face of the coupler, thereby preventing the forcing of said lock out of engagement while under pressure. 65

4. In a car coupler, a head, a recessed lifting pin, a knuckle, and an integral locking device and knuckle-opener, engaging the recess in said pin, said locking device and knuckle-opener resting at all times on the 70 tail of the knuckle and so adjusted that pressure through the knuckle forces said lock against the inner face of the coupler, which in combination with the recess in the lifting pin prevents the forcing of the lock 75 out of engagement while under pressure.

5. In a car coupler, a head, a knuckle, and an integral locking device and knuckle-opener, said locking device and knuckle-opener resting at all times on the tail of the 80 knuckle and so adjusted that pressure through the knuckle forces the said lock against the inner face of the coupler, in combination with a recessed lifting pin, fitting within said coupler, thereby preventing the 85 forcing of said lock out of engagement while under pressure.

6. In a car coupler, a head having a seat on the inside of the shelf, a knuckle, and an integral locking device and knuckle-opener, 90 said locking device and knuckle-opener resting at all times on the tail of the knuckle and so adjusted that pressure through the knuckle forces the said lock against the inner face of the coupler, a recessed lifting pin 95 fitting within said coupler at an angle, a portion of the side of said pin being cut away, whereby when said pin is raised, the shoulder formed by said cut away portion rests on the inside of the shell of the coupler head holding said pin in a vertical position 100 in the path of the knuckle.

Signed by me at Chicago, Illinois, this 14th day of July, 1908.

SAM F. KLOHS.
